US0D1112091S

(12) **United States Design Patent** (10) **Patent No.:** **US D1,112,091 S**
(45) **Date of Patent:** **** Feb. 10, 2026**

(54) **ELECTRIC PLUG**

(71) Applicant: **Shenzhen Grepow Battery Co., Ltd**,
Shenzhen (CN)

(72) Inventors: **Bing Liu**, Shenzhen (CN); **Bing Guo**,
Shenzhen (CN); **Shixing Zhao**,
Shenzhen (CN); **Yunliang Zhu**,
Shenzhen (CN)

(73) Assignee: **Shenzhen Grepow Battery Co., Ltd**,
Shenzhen (CN)

(**) Term: **15 Years**

(21) Appl. No.: **29/959,651**

(22) Filed: **Aug. 27, 2024**

(30) **Foreign Application Priority Data**

Mar. 26, 2024 (CN) 202430160575.4

(57) **CLAIM**

The ornamental design for an electric plug, as shown and described.

DESCRIPTION

FIG. 1 is a front, left and bottom perspective view of an electric plug, showing my new design.

FIG. 2 is a rear, right and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the electric plug

that form no part of the claimed design.

1 Claim, 8 Drawing Sheets
